UNITED STATES PATENT OFFICE.

HENRY MASKE, OF CHICAGO, ILLINOIS.

BURGLAR ALARM AND TRAP.

SPECIFICATION forming part of Letters Patent No. 785,074, dated March 14, 1905.

Application filed February 15, 1904. Serial No. 193,657.

To all whom it may concern:

Be it known that I, HENRY MASKE, a citizen of the United States, residing at Chicago, in the county of Cook and State of Illinois, have 5 invented a new and useful Burglar Alarm and Trap, of which the following is a specification.

My invention relates to improvements in burglar alarms and traps, which comprise an 10 alarm-bell combined with an ordinary door-knob and means whereby the knob can be locked from rotation; and the objects of my improvement are, first, to provide an alarm which can be readily and easily secured in 15 place of an ordinary door-knob; second, to provide means whereby the knob can be used to open the doors or locked against such use at will, and other objects which become apparent from the detailed description to follow. I attain these objects by the mechanism 20 illustrated in the accompanying drawings, in which—

Figure 1. is a fragmental plan view of a door provided with my invention. Fig. 2 is 25 a central section through the knob on line 2 2 of Fig. 1. Fig. 3 is an end view of the knob, partly broken away. Fig. 4 is a cross-section on line 44 of Fig. 2 looking in the direction indicated by the arrows, and Fig. 5 is a 30 cross-section on the same line looking in the opposite direction.

Similar reference characters refer to similar parts throughout the several views.

The door 10 is provided with an ordinary 35 lock having a latch 11, which is operated in the usual manner by the square spindle 12 and the knobs 13 and 14. The knob 13 is an ordinary one; but the knob 14, which is designed to be on the inner side of an outside 40 door, is constructed of the shell 15, provided with the sleeve 16 and the bell 17. The bell 17 forms the front side of the knob, and the shell 15 forms the balance of the knob, and on the interior of said knob 14 is a casing 18, containing a spring which is arranged to be 45 wound up by turning the bell 17 through the medium of the shaft 19, to which the bell and one end of the spring is secured. The casing 18 is rigidly secured to the shell 15 by any 50 well-known means, as the lugs and screws

20. When the spring within the casing 18 is wound by turning the bell 17, it tends to quickly vibrate the hammer or knocker 21 by means of the intervening gear and escape- 55 ment connections 22, which may be of any ordinary construction. The hammer 21 when thus vibrated strikes the bell and causes an alarm.

The parts as thus far described I consider of ordinary construction and shall not at- 60 tempt to make claim to the same.

Rotatably mounted within the sleeve 16 is another sleeve, 23, provided with a square central opening arranged to receive the spindle 12 and secured thereto by the screw 24 in 65 the usual manner. The sleeve 23 is provided within the shell 15 with a collar 25, which is notched at 26 for the reception of one end of the sliding bar 27. The remaining end of the bar 27 is arranged to be moved 70 into a notch 28, provided in the bushing or escutcheon 29, which is rigidly secured to the door 10. The bar 27 is of such length relative to the escutcheon 29 and the collar 25 that when its end is in the notch 28 its other 75 end is out of the notch 26, and vice versa. The sleeve 16 is slotted to provide a way in which the bar 27 is guided.

It will be understood that when the bar 27 is moved so that its end is in the notch 28 80 the knob 14 will be locked to the escutcheon 29, and thus be prevented from being ro- 85 tated, and when the bar 27 is moved so that its end is in the notch 26 the knob 14 will be locked to the spindle 12, and thus can be used as an ordinary knob to operate the latch 11. I preferably provide a screw 30 in the bar 27 as a means to move said bar by the hand.

Projecting longitudinally from the end of 90 the sleeve 23 within the knob 14 are two lugs or pins 31, arranged diametrically opposite one another in a horizontal plane. Secured to the casing 18 are two lugs or ears 32, pro- 95 vided with vertically-concentric perforations for the reception of the rod 33, which has a slight vertical movement. The rod 33 is normally held in its raised position by the coiled expanding spring 34, interposed be- 100 tween a lug 32 and a collar 35, secured to the

rod 33. The upper end of the rod 33 is bent so that its extreme end 36 rests against the under side of an arm 37 of the escapement, which transmits the vibratory movement to the hammer 21. The upward pressure of the spring 34 is sufficient to prevent the escapement from vibrating the arm 37. A horizontal plate or flange 38 is secured to the rod 33 slightly below, and in the same vertical 5 plane with the pins 31, which is depressed by one of the pins 31 when the spindle 12 is rotated in one direction and by the other pin 31 when the spindle 12 is rotated in the opposite direction, providing, however, that 10 the knob 14 is locked to the escutcheon 29. When the flange 38 is depressed, the rod 33, to which it is secured, is moved down, and its extreme end 36 is moved away from the arm 37, allowing said arm, and therefore the hammer 21, to be vibrated by the mechanism already referred to.

From the description it will be seen that the knob 14 can readily and easily be attached to any ordinary door-lock spindle. 25 All that is required to be done is to remove the ordinary knob, file the notch 28 in the escutcheon 29, and attach the knob 14.

I prefer to make the notches 28 and 26 out of alinement, so that repeated slamming of 30 the door cannot accidentally move the bar 27 from one position to the other.

In operation when it is desired to use the invention as an ordinary door-knob the bar 27 is moved so that its end is in the notch 26. 35 When it is desired to use the device as a burglar alarm and trap, the bar 27 is moved so that its end is in the notch 28. If while the device is set in this latter position a thief approaches and turns the outer knob 13, the 40 bell 17 will sound an alarm during the time the knob is being held in a moved position; but as soon as the knob 13 is returned to its normal position by the ordinary means pro-

vided for the purpose in the lock the bell 17 will stop ringing. The thief (we will presume for the purpose of describing the invention) has entered and closed the door after him. Now he is discovered by an occupant of the house. He attempts to open the door and escape; but the knob 14 being locked to 45 the escutcheon 29 the thief cannot escape and is captured.

This device in certain places and at certain times is very valuable.

I am not aware that there has ever been 50 before my invention an alarm known or used of this class which could be applied to any ordinary square lock-spindle without in any way changing or tampering with the lock.

Having fully described my invention, what 55 I claim, and desire to secure by Letters Patent of the United States, is—

The combination of a square spindle; a round sleeve secured to one end of said spindle, a notched flange on one end of said sleeve provided with two longitudinally-extending pins; a sleeve integral with a knob mounted to rotate on said round sleeve, provided with a longitudinal slot; a bolt mounted to slide in said slot; a notch provided on the door to receive the end of said bolt; a notch provided on the knob to receive the other end of said bolt; a spring-actuated mechanism provided with a bell secured in said knob and a trip-lever controlling said spring-actuated mechanism arranged to be moved by said two longitudinally-extending pins.

In testimony whereof I have signed my name to this specification, in the presence of 80 two subscribing witnesses, this 8th day of February, 1904, at Chicago, Illinois.

HENRY MASKE.
